UNITED STATES PATENT OFFICE.

OGLESBY ALLEN, JR., OF CHICAGO, ILLINOIS.

IGNITION-PLUG.

1,314,490.

Specification of Letters Patent. Patented Aug. 26, 1919.

Application filed January 6, 1919. Serial No. 269,766.

To all whom it may concern:

Be it known that I, OGLESBY ALLEN, Jr., a citizen of the United States, and a resident of Chicago, in the county of Cook and State 5 of Illinois, have invented certain new and useful Improvements in Ignition-Plugs; and I do hereby declare that the following is a full, clear, and exact description thereof, reference being had to the accompanying 10 drawings, and to the characters of reference marked thereon, which form a part of this specification.

This invention relates to improvements in spark or ignition plugs for explosion engines, and the invention consists in the combination and arrangement of the parts shown in the drawings and described in the specification, and is pointed out in the appended 15 claim.

20 Among the objects of the invention is to provide an ignition plug which is made of few readily fabricated parts; which is exceedingly durable and rugged; the construction of which is such that the plug elements 25 may be readily taken apart for the purpose of efficiently cleaning the plug elements and the parts of which are so constructed and arranged as to reliably localize and limit the sparking zone at the ends of the terminals. 30

In the drawings,

Figure 1 is a side elevation with parts broken away of an ignition plug embodying my invention.

35 Fig. 2 is a side elevation of a removable assembly of the plug which carries the terminals.

Figs. 3, 4, and 5 are details of a removable element which in part constitutes the ground- 40 ed terminal of the plug.

Reference herein is made to a grounded terminal to indicate what is herein shown as a terminal which is grounded on a metal part of the plug and, in turn, on the engine to 45 complete the circuit, the other terminal being hereinafter designated as the live terminal. This terminology, however, is employed for sake of simplicity of description and is not intended to be limiting.

50 As shown in the drawings, 10 designates

as a whole the body of the plug which is a metal shell-like structure. It is formed with a reduced lower end 11 that is threaded to engage a threaded opening in the cylinder head and is provided at its upper end with 55 a polygonal portion 12 adapted to be engaged by a wrench to thread the shell into the cylinder head. The bore of the shell 10 is formed with an upper enlarged portion 14 which is internally threaded and opens 60 at the top of the shell, a smaller, axially aligned portion 15 which opens through the reduced lower end of the shell. The differential diameters of the bore of the shell produce between the portions 14 and 15 an annular flat shoulder 16.

17 designates as a whole an insulating core which fits partially in the bore of the shell 10. It is formed with a reduced lower end 18 which occupies the smaller diameter 15 70 of the shell bore, a larger intermediate portion 19 which occupies the larger portion 14 of the shell bore, and an extended end portion 20 that extends upwardly beyond the shell. Between the portions 18 and 19 of 75 the core is formed a downwardly facing annular shoulder 21 and between the intermediate portion 19 and the extended portion 20 is formed an upwardly facing annular shoulder 22. 24 designates a tubular nut 80 that is exteriorly threaded to engage the threads of the larger portion 14 of the shell bore and is formed with a polygonal flange 25 for engagement by a wrench. The lower end of the nut engages the upwardly facing shoulder 22 of the core 20 and when screwed down into the shell serves to force the shoulder 21 of the core downwardly toward the internal shoulder 16 of the shell. The said core 17 is made of suitable insulating 85 material. The core is made of such length that the lower or inner end thereof extends well beyond the reduced lower end 11 of the shell.

Said core is axially apertured to receive 95 a close fitting rod 26, the lower or inner end of which extends below or inside said reduced end of the core to constitute the live terminal 27 of the plug. The rod is threaded at its upper end to receive the usual bind- 100

ing nuts, and may be non-rotatably fixed to the core in any suitable or preferred manner.

The grounded terminal or terminals are formed on a member of conducting material that is removably confined in the shell between the shoulders 21 and 16 of the core and shell, respectively. As herein shown, there are two grounded terminals 28 arranged one at each side of the live terminal 27, and they are formed integral with or 10 electrically connected to a flat ring 29 which is of a diameter to snugly fit in the lower unthreaded part of the upper portion of the shell bore. The said terminals are formed 15 at the lower ends of elongated arms 30 which, as shown, are made integral with the ring 29 and the lower ends of said arms are turned inwardly toward the live terminal to constitute the grounded terminals. 20 Preferably and as herein shown, the said arms are formed at their inner sides as cylindric segments of a radius to fit the reduced lower end of the core. Such configuration of the grounded terminals abreast 25 the live terminal is also favorable for proper sparking between the terminals. The said arms 30 are also shown as convexly curved on their outer sides and fit closely the smaller circular portion 15 of the shell bore, 30 being confined between the inner wall of the said reduced portion of the bore and the lower reduced portion 18 of the insulating core 17. This construction serves to hold the arms, which are in themselves preferably of suitable stiffness, rigidly in place 35 relative to the live terminal.

To remove the operative parts of the plug the nut 25 is unscrewed from the shell, whereupon the core, carrying the live terminal, may be readily lifted away from the shell. Thereafter the ring 29 which carries the grounded terminals may be lifted out of the shell. Said terminals, when thus removed from the shell, are free to be cleaned as separate parts, and the bore of the shell may be also readily cleaned by running a cleaning brush or swab therethrough, as will be apparent. When the parts are cleaned the ring 29, carrying the terminals 28, is dropped into the shell upon the shoulder 16, after which the core is inserted into the shell with the lower reduced end between the arms 30 and with the downwardly facing shoulder 21 thereof resting against the upper face of the ring. Thereafter the nut 25 is screwed down against the upwardly facing shoulder 22 of the core which serves to force the ring 29 in close contact with the shoulder 16 of the shell bore. It will thus be observed that a very good electric contact is maintained between the grounded terminal device and the shell, which contact occurs at the flat meeting faces of the ring and coacting shoulder, between the periphery of

the ring and the unthreaded portion of the 61 shell and between the arms 30 and the inner wall of the reduced portion 11 of the shell.

One advantage of the construction described is due to the removability of the core and all of the terminals freely upwardly from the shell so that when the plug is disassembled said terminals may be freely cleaned of carbon deposits. Another advantage of the particular embodiment of the invention shown is due to the fact that when 70 the core and terminals are withdrawn free access may be had to the shell bore to thoroughly clean the same without liability of destroying the relative positions of the terminals when the operative parts are again 75 assembled, such as is likely to occur in known forms of ignition plugs in which the grounded terminals are fixed to and carried by the shell. A further advantage of the construction disclosed is the means by which the 80 grounded terminal device is clamped between the shell and the insulating core and which permits ready removal of said core and the grounded terminal device and convenient assembling of said parts. Another 85 advantage of the construction shown is due to the bracing of the arms which carry the 90 grounded terminals. In this connection it will be noted that said arms are made of substantial cross section so that they are in 95 themselves quite stiff which, taken in connection with the close confining of the arms along their length between the shell and core insures a definite or non-varying spacing of the terminals. A further advantage 100 of the construction is found in the fact that the terminals 27 and 28 extend beyond both the core 30 and the metallic shell and are definitely spaced a distance apart at their ends less than the distance of protrusion of 105 the core from the shell. Therefore the terminals are subjected to the direct action of the explosion in the engine cylinder and, being relatively narrow, are in the influence 110 of the localized effects of sparking so as to be kept free from carbon deposits in all parts thereof that project beyond the core and thereby limit or localize the sparking area at the ends of the sparking terminals.

I claim as my invention:

An ignition plug for explosive engines comprising a metallic shell formed with an upper enlarged and a lower reduced bore and with a shoulder between them, a one-piece insulating core formed with a part of larger 120 diameter to fit within the enlarged diameter of the shell, with a part of reduced diameter to fit within the reduced diameter of the shell, and with a shoulder therebetween to oppose the shell shoulder, said core extending at its inner end beyond the inner end of the shell and freely withdrawable through the outer end of the shell, a live terminal

extending axially through the core and beyond the inner end thereof, and a ring clamped between the shell and core shoulders and provided with angularly spaced 5 arms which are confined and braced between the core and shell and in contact with the shell and extending beyond the core, said arms being turned at their free ends to-
ward each other and the live terminal and spaced from the live terminal to constitute 10 the grounded terminals of the plug.

In testimony whereof I claim the foregoing as my invention, I hereunto append my signature at Chicago, Illinois, this second day of January, 1919.

OGLESBY ALLEN, Jr.
